ATTORNEY.

UNITED STATES PATENT OFFICE

CHARLES KNIGHT, OF DENVER, COLORADO

ORE FURNACE CONSTRUCTION

Application filed July 22, 1929. Serial No. 379,904.

This invention relates to ore furnaces, more particularly of the type illustrated in applicant's co-pending application, Serial No. 315,684, now Patent No. 1,764,313, June 17, 1930, and has for its principal object the provision of means and method for heating a roasting cylinder or drum whereby oxidation or burning of the drum is eliminated and wherein the fire or flame never comes in contact with the drum metal.

Another object of the invention is to so construct the heating portion of the furnace that a uniform degree of heat is obtained throughout the length of the drum.

15 A further object of the invention is to provide a heater construction for ore furnaces which will allow heated gases to be withdrawn for use in other operations in the plant.

A still further object of the invention is 20 to provide means so that the temperature at any portion of the drum can be minutely controlled.

Other objects and advantages reside in the detail construction of the invention which is 25 designed for simplicity, economy, and efficiency. These will become more apparent from the following description.

In the following detailed description of the invention reference is had to the accompanying drawings which form a part hereof. Like numerals refer to like parts in all views 30 of the drawings and throughout the description.

In the drawings:—

35 Fig. 1 is a plan view of the heating portion of an ore furnace designed to support a cylindrical roasting drum. The novelty of the present invention resides in the unique construction of this portion of the furnace.

40 Fig. 2 is a longitudinal section therethrough taken on the line 2—2, Fig. 1. In this view the position of a typical roasting drum is indicated in broken line.

45 Fig. 3 is a vertical cross section, taken on the line 3—3, Fig. 1, with the roasting drum indicated in position at 10.

The mechanism for feeding and operating the drum and the details of the drum itself have not been illustrated since they form no 50 part of the present invention. These are

more fully described in applicant's co-pending application, Serial No. 315,684. The position of the discharge chute from the drum is indicated in broken line at 11 and the excavation for the conveyor which removes the 55 roasted ore from under the discharge is illustrated at 12.

The drum is supported in sockets 30 between two brick side walls 13 and a brick back wall 14. The entire interior construction inside of the brick walls is formed of heat resisting fire clay and comprises interior side walls 15 and 16 and a back wall 17. Extending between the fire clay interior walls 15 and 16 is a fire clay arch 18 which divides the 60 entire structure into a hot gas chamber 19 and a fire chamber 20. The fire chamber 20 terminates short of the back wall 17 as shown at 21 to allow space for the discharge chute 11. The drum 10 forms the roof of the hot 65 gas chamber 19.

Below the arch 18 the side walls 15 and 16 extend inwardly into the fire chamber 20 in a series of baffles 22. A series of heat spaced 70 apart passages 23 extend upwardly in each of the side walls from the channels between the baffles 22 and open to the hot gas chamber 19. At the forward extremity of the furnace the heating chamber 20 extends forwardly 75 forming a fire box 24 into which an oil burner 25 projects a flame.

Immediately over the burner nozzle 25 will be an area of comparatively low temperature owing to the fact that the gases at this point have not completely burned. By extending the fire box forwardly from the furnace this low temperature area is not positioned under the roasting cylinder so that uniformity of heat thereunder is obtained.

80 The burner 25 projects a flame lengthwise into the heating chamber 20. Sufficient oxygen is admitted with the oil to allow for complete combustion. The burner nozzle is of any of the usual types in which the amount of air being admitted can be closely regulated so that there will be no excess oxygen in the heating chamber. In use, the entire hot 85 gas chamber 13 is filled with non-oxidizing combustion gases such as CO₂, CO, etc. There is no free oxygen in this chamber. Thus, 90

since there is no oxygen, corrosion can not take place upon the metal of the drum and insulation of the drum is unnecessary. This greatly increases both the efficiency of the furnace and the life of the drum.

5 The blast of hot gases from the burner nozzle passes all of the baffles 22 each of which abstracts a portion of the heat therefrom and directs it upwardly through its passage 23. The projection of the baffles 22 into the flame area causes them to become highly heated so that they will also transmit heat to the fire clay walls of the hot gas chamber. Thus, heat is supplied to the hot gas chamber uniformly throughout its length to bring the temperature therein to any desired point and since the bottom of the drum 10 is directly exposed to the hot gases in the chamber 19 it will be efficiently and uniformly heated throughout its length.

10 It will be noted that the above construction of the heating portion of the furnace accomplishes several functions. First, no oxygen is brought into contact with the heated 25 roasting cylinder so that oxidation and corrosion of the cylinder is eliminated; second, no flame or combustion takes place in close proximity to the metallic cylinder wall so that there is no tendency to burn away the 30 metal thereof; third, the heat is admitted to the hot gas chamber substantially uniformly and at a multitude of points throughout its length so that a uniform heat is obtained throughout the entire length of the cylinder; fourth, the temperature of the cylinder 35 can be easily and minutely controlled throughout its length by simple adjustment of the burner nozzle and the oil and air supply thereto.

40 In the fire clay side walls 15 and 16 a series of vertical exhaust passages 26 may be formed which extend above the walls as stacks 27 controlled by means of dampers 28. These stacks and passages are not ordinarily 45 necessary for the operation of the furnace but serve as outlets for hot gases for conveying heat to other apparatus about the plant such as for preheating the ore before introduction, heating solutions, etc. They 50 also may be used as an additional control of the temperature throughout the length of the furnace. For instance, should it be desired to increase the heat at the rear end of the cylinder the dampers in the stacks at 55 this point could be slightly opened to create a draft which would draw the hot gases toward this extremity, or by manipulation of the front dampers the gases could be carried to the front of the cylinder.

60 The top of the roasting cylinder may be protected by suitable insulation as indicated at 29 as is usual in ore roasting furnace construction, if desired.

65 While a specific form of the improvement has been described and illustrated herein, it

is desired to be understood that the same may be varied, within the scope of the appended claim without departing from the spirit of the invention.

Having thus described the invention, what 70 is claimed and desired secured by Letters Patent is:—

An ore furnace comprising: a combustion chamber; an arch over said combustion chamber; a hot gas chamber above said arch; a 75 roasting drum covering said hot gas chamber; a series of passages at each side of said arch communicating between said two chambers; a series of stacks opening at spaced apart points throughout the length of said 80 hot gas chamber; and means for individually controlling said stacks so as to draw off gases at any desired points throughout the length of said hot gas chamber, said stacks communicating through the side walls of said hot gas 85 chamber at each side of the latter and at spaced apart intervals throughout its length.

In testimony whereof, I affix my signature.

CHARLES KNIGHT.
